UNITED STATES PATENT OFFICE.

PAUL DE HEMPTINNE, OF GHENT, BELGIUM.

APPARATUS FOR CASTING HOLLOW METAL BODIES.

SPECIFICATION forming part of Letters Patent No. 743,077, dated November 3, 1908.

Application filed November 13, 1902. Serial No. 131,099. (No model.)

To all whom it may concern:

Be it known that I, PAUL DE HEMPTINNE, a subject of the King of Belgium, residing at Ghent, Kingdom of Belgium, have invented 5 certain new and useful Improvements in Apparatus for Casting Hollow Metal Bodies, fully described and represented in the following specification and the accompanying drawings, forming a part of the same.

10 This invention relates to apparatus for casting hollow ingots, particularly of steel or other metals. Attempts have been made heretofore by others to produce an apparatus for casting such ingots by the use of a rotating mold; but such attempts have not to my knowledge been successful. The failure of such attempts has been largely if not entirely, due to the rapid cooling of the molten metal before a proper distribution thereof in 15 the mold has been effected and to vibrations or variations in speed of rotation of the mold. My invention avoids these difficulties and provides a practically successful apparatus for accomplishing the desired operation.

20 As a full understanding of the invention can best be given by a detailed description of a construction embodying the features of the invention in the preferred form, such a description will now be given in connection 25 with the accompanying drawings, showing such an apparatus.

In said drawings, Figure 1 is a central longitudinal sectional view. Fig. 2 is a sectional view taken on the line 2 of Fig. 1, and Fig. 3 is an enlarged detail sectional view of one 30 of the roller-bearings.

Referring to the drawings, the mold is preferably formed of a cylindrical tube 10 of suitable material, having at one end a cap 11, 35 which carries a hollow shaft 12, and having at the other end a cap 13, formed with a central opening 14 for the introduction of the molten metal. The caps 11 and 13 are preferably both removably secured to the ends of 40 the tube 10 to permit of their being taken off for removing the cast ingot from the mold and for permitting caps 13 having different-size openings 14 to be used and for permitting different mold-tubes to be used with the 45 same caps.

The shaft 12 is rotatably mounted in a universal bearing—that is, a bearing adapted to

55 permit slight changes in the direction of the axis of the mold without interfering with the adjustment of the bearing, without producing any binding in the bearing which might result in variations of speed of rotation of the mold, and without permitting any play in the bearing. For this purpose the shaft preferably carries a bearing-sleeve 15, which is journaled in a bearing-block 16, the bearing-faces of which sleeve and block are in the form of a central zone of a sphere. The shaft 12 also carries a driving-pulley 17. The mold is also supported by a bearing which engages an annular bearing on the body of the mold at a point between the ends thereof and nearer the entrance end and is constructed so as to be automatically expandable to accommodate itself to the expansion and contraction of the 60 mold due to heating and cooling. For this purpose there is preferably provided a roller-bearing comprising, preferably, three rollers, 18, arranged triangularly, and one at least held in place under yielding tension, which 65 will permit it to move away from the other two for the purpose of causing the bearing to accommodate itself to the expansion and contraction of the mold-body. The two stationary bearing-rolls are preferably arranged substantially in the same horizontal plane and serve as supporting-rolls for the mold, and the movable bearing-roll is preferably carried by a bracket or arm 19, pivoted at one side of the mold and extending over the mold and pressed downward by means of a spring 20, which is held under adjustable tension by means of a screw-collar 21 on an upwardly-projecting pivoted rod 22. The arm 19 and rod 22 are or may be mounted on a frame 23, which supports the two stationary bearing-rolls. The bearing-rolls 18 are preferably mounted on antifriction ball-bearings, which may be of any suitable construction or as shown in Fig. 3.

70 The molten metal is introduced into the mold through a nozzle 25, which is mounted to project through the opening 14 and into the mold, extending with its end some distance inside the inner face of the cap 13. The nozzle 25 is preferably slightly inclined and tapered and connects with a hopper or chamber 26, into which the metal is poured. The opening 14 should be of such size with

relation to the nozzle 25 as to leave an air-passage around the nozzle for permitting air to be drawn into the mold with the molten metal, such air escaping through the hollow shaft 12 and aiding by its movement through the mold in the rapid distribution of the molten metal.

In the operation of the apparatus the mold is first started rotating at a high rate of speed, 10 which should be not less than six hundred to seven hundred and fifty revolutions per minute. The molten metal is then introduced into the mold through the nozzle 25. As the metal enters the mold it will be thrown against 15 the sides of the mold, and aided by the entrance of air through the opening 14 around the nozzle and the exit of air through the hollow shaft 12 the metal will advance rapidly in the mold in a spiral path to form a 20 body having an outside shape corresponding to the inner surface of the mold and having a central longitudinal opening therethrough.

The size of the nozzle should be varied according to the size of the ingots to be cast 25 and it should extend more or less into the mold. The size of the opening 14 also should be varied according to the size of the nozzle and the speed of entrance of the metal and rotation of the mold.

30 What I claim is—

1. In an apparatus for casting hollow ingots, the combination of a horizontally-arranged mold having a central opening at one end, a universal bearing in which the opposite end of the mold is self-adjustably journaled, an automatically-expansive bearing having an odd number of bearing members for engaging and supporting the body of the mold at a point between the ends thereof 35 whereby the mold is capable of being rotated at great speed without vibration, a nozzle for introducing molten metal through the central opening in the end of the mold, and means for rotating the mold, substantially as described.

2. In an apparatus for casting hollow ingots, the combination of a horizontally-arranged mold having a central opening at one end, a universal bearing in which the opposite end of the mold is self-adjustably journaled, an automatically-expansive bearing having an odd number of bearing members for engaging and supporting the body of the mold at a point between the ends thereof 50 whereby the mold is capable of being rotated at great speed without vibration, a nozzle adapted to extend through the central opening into the mold-chamber beyond the inner face of the end of the mold, the nozzle and said opening being of a size to provide an air-inlet around the nozzle and the mold being provided at its opposite end with an air-outlet, and means for rotating the mold, substantially as described.

65 3. In an apparatus for casting hollow ingots, the combination of a horizontally-arranged mold having one end partially closed

by a cap having a central opening, a universal bearing in which the opposite end of the mold is self-adjustably journaled, an automatically-expansive bearing having an odd number of bearing members for engaging and supporting the body of the mold at a point between the ends thereof whereby the mold is capable of being rotated at great speed 70 without vibration, a nozzle adapted to extend through the central opening in said cap into the mold-chamber beyond the inner face of said cap, the nozzle and the opening being of a size to provide an air-inlet around the nozzle and the mold being provided at its opposite end with an air-outlet, and means for rotating the mold, substantially as described.

4. In an apparatus for casting hollow ingots, the combination of a horizontally-arranged mold having a central opening in one end, a bearing in which the other end of the mold is self-adjustably journaled, a bearing supporting the body of the mold between the ends thereof, having three members and means permitting one of said members to move away from the other two against yielding tension whereby the bearing will automatically accommodate itself to the expansion and contraction of the mold, a nozzle 85 for introducing molten metal through the central opening in the end of the mold, and means for rotating the mold, substantially as described.

5. In an apparatus for casting hollow ingots, the combination of a horizontally-arranged mold having a central opening in one end, a bearing in which the other end of the mold is self-adjustably journaled, a bearing supporting the body of the mold between the ends thereof comprising a pair of stationary bearing-rolls and a third bearing-roll for engaging the opposite side of an annular bearing-surface on the mold and movable away from the pair of rolls against yielding tension 105 whereby the bearing will automatically accommodate itself to the expansion and contraction of the mold, a nozzle for introducing molten metal through the central opening in the end of the mold, and means for rotating 110 the mold, substantially as described.

6. In an apparatus for casting hollow ingots, the combination of a horizontally-arranged mold having one end partially closed by a cap having a central opening, a bearing 120 in which the other end of the mold is self-adjustably journaled, a nozzle adapted to extend through the opening in the cap into the mold beyond the inner face of said cap, a bearing supporting the body of the mold between the ends thereof having three bearing members and means for permitting one of said members to move away from the other two against yielding tension whereby the bearing will automatically accommodate itself to the 125 expansion and contraction of the mold, and means for rotating the mold, substantially as described.

7. In an apparatus for casting hollow in-

gots, the combination of a horizontally - arranged mold suitably journaled at one end in a universal bearing and having its other end partially closed by a removable cap having a central opening, an automatically-expansive bearing having an odd number of bearing members for engaging and supporting the body of the mold at a point between the ends thereof, whereby the mold is capable of being rotated at great speed without vibration, a nozzle for introducing molten metal through said central opening, and means for rotating the mold, substantially as described.

15 8. In an apparatus for casting hollow ingots, the combination of a horizontally - arranged mold suitably journaled at one end in a universal bearing and having its other end partially closed by a removable cap having a central opening, an automatically-expansive bearing having an odd number of bearing members for engaging and supporting the body of the mold at a point between the ends thereof, whereby the mold is capable of being rotated at great speed without vibration, a nozzle for introducing molten metal through said central opening, said nozzle and opening being of a size to provide an

air-inlet around the nozzle and the mold being provided at its opposite end with an air-outlet, and means for rotating the mold, substantially as described.

9. In an apparatus for casting hollow ingots, the combination of a horizontally - arranged mold suitably journaled at one end in a universal bearing and having a central opening in the other end thereof, a bearing supporting the body of the mold between the ends thereof, said bearing being provided with an odd number of bearings and adapted to automatically accommodate itself to the expansion and contraction of the mold, a nozzle for introducing molten metal through the central opening, said nozzle and the opening being of a size to provide an air-inlet around the nozzle and the mold being provided at its opposite end with an air-outlet, and means for rotating the mold, substantially as described.

In testimony whereof I have hereunto set my hand in the presence of two subscribing witnesses.

PAUL DE HEMPTINNE.
